UNITED STATES PATENT OFFICE.

EDWARD JOHN WAY, OF JOHANNESBURG, TRANSVAAL, SOUTH AFRICA.

DELIVERING AND WINDING CINEMATOGRAPH FILM.

1,415,131.

Specification of Letters Patent.

Patented May 9, 1922.

Application filed November 26, 1920. Serial No. 426,580.

To all whom it may concern:

Be it known that I, EDWARD JOHN WAY, a British subject, residing at 134 to 136 Cullinan Buildings, Simmonds Street, Johannesburg, Transvaal Province of the Union of South Africa, have invented certain new and useful Improvements in Delivering and Winding Cinematograph Films for Projection, of which the following is a specification.

The present invention has reference to the process of taking cinematograph film from an unused coil, and, after projecting it for exhibition, winding the same as a used coil. As is well known the method at present commonly employed is to withdraw the film from the outer periphery of the unused coil and to wind it upon the spool for the used coil. Consequently the resulting used coil is wound reversely from the unused coil from which it was formed and before it can be re-projected has to be rewound upon another spool so as to bring to the outside that end of the film which comes inside the used coil first formed but which was outside the original unused coil; in other words, the re-winding reconstructs the original unused coil.

The extensive damage which films suffer in use, occurs principally during this operation of re-winding. The rewinding is effected at a high rotational speed which frequently results in the film being broken or kinked; and when kinking occurs the film is liable to break at the same point upon next being passed through the projector. In placing the coil upon the reel for re-winding or taking it off the same, the coil is frequently drawn out axially in a cone; and beating in this cone to bring it flat causes horizontal striation of the film. Also the coil is wound with uneven tension and in order to make it uniform the operator twists it up by hand, resulting in vertical striation on the emulsion.

It is an object of the present invention to do away with this re-winding of the film and its attendant drawbacks, by so delivering and winding the film that the unused and used coils are identical with one another, thus enabling the used coil to be re-projected without any further treatment.

The invention is illustrated in the accompanying drawings in which—

Fig. I is a side elevation of a projector embodying this invention.

Fig. II is a side elevation of the unused coil carrier, showing its attached parts in a different position from Fig. I.

Fig. III is a plan view of Fig. II. 60

Fig. IV is a plan of the unused coil carrier with parts broken away to exhibit the construction, and holding a shorter film than that shown in the other figures.

Fig. V shows a form for setting the apparatus.

Referring to Fig. I, 1 indicates the projector through the gate 2 of which the film is fed by mechanism 3. 4 indicates the prime mover which is shown as a hand crank 70 and which is positively connected to the feed mechanism 3 to drive the same. 5 indicates the unused coil mounted upon a carrier 6, and 7 indicates the used coil wound upon a spool 8 which is driven in the usual manner through a slipping clutch. The loop of film between the coil 5 and the projector is designated by 9.

The invention consists primarily in delivering film from the internal periphery of the unused coil 5 at a linear speed which is equal to the speed of the film due to the feed mechanism 3. After projection the film is wound in the usual way onto the spool 8 so that the used coil becomes at once a 85 replica of the unused coil.

For thus delivering the film the following mechanism is provided: 10 is a shaft which is driven positively by gearing 11, 12, 13 from the prime mover 4. It is squared 90 to slide through the gear wheel 13 and can both slide and rotate in the fixed bearing 14 on the frame 15. On said shaft 10 is a friction wheel 16 which drives a friction disc provided, in the mechanism shown, by the 95 under surface 17 of the carrier 6 thereby rotating the same to cause the delivery of film from the coil 5. As said friction wheel 16 is rotated, it is also moved radially outwards in regard to the carrier 6 so that the 100 angular speed of the carrier is constantly reduced in inverse ratio to the increase of the internal periphery of the unused coil 5, so keeping constant the linear speed of delivery of the film from the interior of said 105 coil 5.

The radial position of the friction wheel 16 is directly governed by the internal diameter of the unused coil 5. For this purpose the shaft 10 is provided with rigid 110 flanges 18 embracing between them an arm 19 which projects beyond them and carries

a rotatable spindle 20. Said spindle 20 is formed with a screw thread 21 by which it is secured to a slipper 22 carried for sliding movement on a guide 23 and steadied by engagement with the shaft 10. Said slipper carries an arm 24 on the end of which is a roller 25 which bears against the internal periphery of the coil 5. A light weight 26 or other appropriate device constantly urges the slipper 22 and its attached parts viz., the arm 24 and the friction wheel 16 radially outwards with regard to the coil 5. Said weight 26 is preferably such that it cannot produce movement of the friction wheel 16 until such movement is facilitated by rotation of the carrier 6. The friction wheel 16 is arranged at the same radial distance as the contact line of the roller 25. As film is withdrawn from the internal periphery of the coil 5 the roller 25 is still kept by the weight 26 in contact with the same and thus moves radially outwards, so keeping the friction wheel 16 at all times at the same radial distance as the internal periphery of the coil 5.

The arm 24 is hinged at 27 to enable its end carrying the roller 25 to be inserted into or withdrawn from the interior of the coil 5. A ball 28 or other anti-friction bearing is provided at the bottom of the roller 25 and the arm 24 is adjustably counter-weighted by a rod 29 pivotally clamped at 30 so that it can be positioned to exert pressure with, or oppositely to, the arm 24. It is important that the roller 25 should not bear on the picture area of the film, which would tend to wear or mark the same; and accordingly said roller is cut away at its mid-part 31 opposite the picture bearing area of the film, leaving the ends 32 to contact with the marginal strips 33 of the film.

The carrier 6 is preferably horizontally disposed as shown, to facilitate placing the coil 5 upon it and also to permit the roller 25 to be retained in place by gravity. In order to prevent the internal turns of the coil 5 from lifting and so becoming improperly positioned in regard to the surfaces 32 of the roller 25, said roller is formed at its upper end with a flange 34 which overlaps a few turns of the coil.

It is essential for the proper working of the apparatus that the velocity ratio between the friction wheel 16 and the carrier 6 should be accurate to a very high degree. As an illustration, it may be mentioned that, with a film 1500 feet long, a discrepancy in the radial distances of the roller 25 and the friction wheel 16, equal to the thickness of the film, would result in the loop 9 being varied in length by nearly 5 inches. The drawings show two adjustments for the accurate setting of the friction wheel 16 in relation to the roller 25. For first setting the friction disc, the same is mounted on the

shaft 10 by means of a fine screw thread 35 and is locked by nuts 36. Supposing the friction wheel 16 to be six inches in diameter and the screw 35 to have a pitch of $\frac{1}{24}$ of an inch, a movement of $\frac{1}{8}$ of an inch measured at the periphery of the wheel would effect a linear adjustment of the wheel along the shaft 10 of roughly .0003 of an inch. This adjustment would be employed for first setting the apparatus in the manner hereafter described. For enabling the operator to make fine adjustments whilst the apparatus is at work the connection between the shaft 10 and the slipper 22 is made by the screw spindle 20 above referred to. The screw 21 has a fine thread of, say, 48 to the inch; and the spindle 20 is fitted with a hand wheel 37 of large diameter which is held in position by a spring detent 38 taking in notches,—of which there may be say 112,—on the periphery of the hand wheel 37. This arrangement enables the operator at any time to adjust the radial position of the friction wheel by .00015 of an inch which is within the limits of accuracy necessary.

The carrier 6 seats on the square end 39 of a spindle 40 mounted for free rotation in the frame 15 and formed with a shoulder 41 which supports the carrier. Said shoulder 41 is of such height in relation to the friction wheel 16 that the carrier, when seated on said shoulder, exerts the necessary slight driving pressure on the friction disc. The friction wheel 16 is thus virtually diminished in diameter by an amount which, though small, must be taken account of, and which must be prevented from materially varying. To this end the adjustable counterweight 29 is provided to control the downward pressure of the arm 24 and roller 25 on the carrier 6.

In order to permit the insertion of the roller 25 into the interior of the coil 5, the initial internal diameter of said coil is made greater than is at present usual with cinematograph coils; a diameter of about 4 inches having been found convenient. The reel 8 upon which the used coil is wound is accordingly formed with a core 42 of about this diameter. The precise diameter of said core is, however, immaterial since the roller 24 automatically adjusts the friction wheel 16 to whatever diameter of coil is placed upon the carrier 6. Said core 42 is also made collapsible in order to facilitate the removal of the used coil from it. For this purpose it is formed of a spring strip rigidly secured at one end to the cheek 43 of the reel 8. Said strip springs outwards against stops 44 on said cheek 43 which determine its maximum diameter. The ends of the strip are formed with ears 45 by pressing which together the core is collapsed, so permitting the used coil to be withdrawn from it without force. The extreme ends 46 of

the strip, when sprung together, form a clip to hold the end of the film.

Means are provided for accurately centering the coil 5 upon its carrier 6 by means of its external periphery. For this purpose there is shown a device in the nature of an iris diaphragm consisting of a number of segments 47 each secured at one end to the carrier 6 and at the other end to a rotatable ring 48. Such a device provides a considerable range of expansion and contraction whilst at all times presenting an inner periphery closely approximating to a circle. In view of the explained mechanical accuracy necessary for the successful operation of the device it is important that the peripheral surfaces 32 of the roller 25 should not come into contact with the iris diaphragm or other parts of the carrier when the last coil 20 of the unused film is withdrawn and to this end the central part 31 of the roller is arranged to contact with the iris diaphragm and keep said surfaces 32 out of contact with parts of the mechanism. As a measure of safety there is provided, on a standard 49, a platform 50 which limits the downward movement of the weight 26 and which can be adjusted by the operator with regard to the external diameter of the film coil 5 that movement of the slipper 22 ceases when the last few turns of coil are about to be projected.

In first setting the device there is centered upon the carrier 6 a metal form 51 (Fig. V) having the same internal diameter as the standard unused coil which would be used upon the machine. If the direction wheel 16 has a resilient peripheral portion, said form 51 would also be made of about the same weight as a full coil of film so as to impress said peripheral portion to about the normal extent. The roller 25 is then placed in contact with the internal periphery of the form, the prime mover 4 is rotated, and the revolutions of the prime mover and the carrier 6 are counted. The standard speed of projecting film is 60 feet per minute and the standard angular speed of the crank handle 4 is 120 revolutions per minute. With an internal diameter of 3.819 inches, the form 51 and carrier 6 should accordingly rotate 60 times per minute. The friction wheel 16 is adjusted longitudinally of the shaft 10 by means of the screw 35 until this correspondence is arrived at. Then, since the radial distance of the friction wheel 16 is directly governed by that of the internal periphery of the coil 5, the apparatus will deliver film substantially at the desired linear speed for any diameter within its range. The operator can observe the loop 9 during projection and should he find either a decrease or increase in its size he can at once make the necessary fine adjustment to correct it by means of the hand wheel 37.

The film having been wound upon the roller 8 is at once in condition to be placed upon the carrier 6 and led through the projector 1 without re-winding. While the friction wheel 16 is being returned to its inner radial position, the carrier 6 is revolved to facilitate the movement of said wheel 16 across it.

I claim.

1. In cinematograph apparatus, the combination with a frame, of a coil carrier mounted to rotate thereon about a substantially vertical axis and providing a friction disc, a driving shaft mounted radially on the frame, a friction wheel on the shaft engaging the friction disc and movable radially of the carrier, means adapted to engage the interior of a film on the carrier and movable radially rigidly with the friction wheel as the film is unwound from the center of the coil, and driving mechanism for the shaft.

2. In cinematograph apparatus, the combination with a frame, of a coil carrier mounted to rotate thereon about a substantially vertical axis and providing a friction disc, a driving shaft mounted radially on the frame, a friction wheel on the shaft engaging the friction disc, a carriage movable radially on the frame, said friction wheel being rigidly connected to the carriage for radial movement, an arm pivoted to the carriage and carrying at its end a roller adapted to enter a film coil on the carrier and govern the radial movement of the carriage, and driving mechanism for the shaft.

3. In cinematograph apparatus, the combination with a frame, of an open topped coil carrier mounted thereon for rotation about a vertical axis, a carriage slidable on the frame radially of the carrier, a pivoted arm extending from the carriage towards the carrier and carrying a roller arranged to make contact with the interior of a film coil on the carrier, a shaft slidable radially of the carrier and connected for such sliding movement to the carriage, a friction wheel on the shaft and engaging the under surface of the carrier, and a gear wheel mounted on the frame for rotational movement only and engaging the shaft to rotate the same.

4. The process which consists in delivering film from the internal periphery of the unused coil, passing said film through a projector, rotating the unused coil at an angular speed governed by the internal diameter of said unused coil and winding the film upon the external periphery of the used coil.

5. In cinematograph apparatus, the combination with a projector and mechanism for feeding film therethrough, of a carrier for unused film, variable speed friction gear for driving said carrier with the film feeding mechanism, and means adapted to be held in contact with the internal periphery

of a film coil on the carrier for governing the variable speed friction gear as the film is unwound from the center of the coil.

6. In cinematograph apparatus, the combination with a projector and mechanism for feeding film therethrough, of a rotatable carrier for unused film, a friction disc rotating with the film carrier, and a friction wheel engaging the friction disc and driven 10 at a uniform speed relatively to the film feeding mechanism, said friction wheel being traversible radially of the friction disc in accordance with the internal diameter of the coil on the carrier as the film is unwound from the center of the coil.

7. In cinematograph apparatus, the combination with a projector and mechanism for feeding film therethrough, of a rotatable film carrier, a friction disc rotating with the 20 film carrier, means to make contact with the internal periphery of a coil on the carrier, and a friction wheel engaging the friction disc and arranged at the same radial distance as said contact means, said friction wheel and contact means being rigidly connected and being movable radially of the friction disc, as the film is unwound from the center of the coil.

8. In cinematograph apparatus, the combination with a projector, a prime mover, film feeding mechanism positively driven by 30 said prime mover, a shaft positively driven by said prime mover, a friction wheel on said shaft and movable axially thereof, a rotatable carrier for unused film, a friction disc rotatable with said carrier, said friction wheel engaging said friction disc and being movable radially thereof, and means controlled by the internal diameter of a coil 40 on the carrier for restraining outward movement of the friction wheel as the film is unwound from the center of the coil.

9. In cinematograph apparatus, the combination with a projector, a prime mover, film feeding mechanism positively actuated 45 by said prime mover, a shaft positively rotating with said prime mover, a rotatable carrier for unused film, a friction disc rotatable with said film carrier, a friction wheel on said shaft, said shaft being movable longitudinally to shift the friction wheel radially of the friction disc said friction

wheel being minutely adjustable longitudinally of the shaft.

10. In cinematograph apparatus, the combination with a projector, a prime mover, film feeding mechanism positively actuated by said prime mover, a rotatable carrier for unused film, a friction disc rotatable with said film carrier, a friction wheel engaging 60 said friction disc and positively rotated by the prime mover, means to contact with the internal periphery of a film coil on the carrier, said contact means and the friction wheel being movable together radially of 65 the carrier and the friction disc, and means for minutely adjusting the relative radial positions of the contact means and the friction wheel.

11. In cinematograph apparatus, the combination with a projector, film feeding mechanism therein, a rotatable carrier for unused film, a friction disc rigid therewith, a shaft positively rotating with said film feeding mechanism, a slipper movable longitudinally with the shaft, an arm pivoted to said slipper and carrying a roller adapted to enter the interior of a film coil on the carrier, and a friction wheel rigid with the shaft and engaging the friction disc, 80 and the shaft and associated parts being movable radially of the friction disc and the film carrier.

12. In cinematograph apparatus, a film carrier, variable speed friction gear for driving the same, means governing the friction gear and adapted to contact with the internal periphery of a film coil on the carrier, means tending to move said contacting means radially outwards with respect to 90 the film coil and adjustable means for limiting the outward movement of said contacting means.

13. In cinematograph apparatus, the combination with a projector, of a prime mover, 95 a carrier for the unused coil driven by said prime mover, a ring rotatable on the carrier, and a plurality of arcuate bars each pivoted to the carrier at one end and to the ring at the other end, said bars defining an approximately circular space centrally of the 100 carrier for the reception of a film coil.

In testimony whereof I affix my signature.
EDWARD JOHN WAY.
